(57) **CLAIM**

The ornamental design for a bedside sleeper as shown and described.

DESCRIPTION

FIG. 1 is a first perspective view of a bedside sleeper, showing our new design within an environment of use in a first condition of use;

FIG. 2 is a rear perspective view thereof;

FIG. 3 is a front perspective view of a bedside sleeper, showing our new design in a first condition of use;

FIG. 4 is a rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a front perspective view of a bedside sleeper, showing our new design within an environment of use in a second condition of use;

FIG. 12 is a rear perspective view thereof;

FIG. 13 is a front perspective view of a bedside sleeper, showing our new design in a second condition of use;

FIG. 14 is a rear perspective view thereof;

FIG. 15 is a front view thereof;

FIG. 16 is a rear view thereof;

FIG. 17 is a left side view thereof;

FIG. 18 is a right side view thereof;

FIG. 19 is a top view thereof; and,

FIG. 20 is a bottom view thereof.

The broken lines in the drawings depict environmental subject matter that form no part of the claimed design. The shade lines in the drawings show contour and not surface ornamentation.

1 Claim, 14 Drawing Sheets
